CLAIM

The ornamental design for a bed for animals, as shown and described.

DESCRIPTION

FIG. 1 is a top, front, right perspective view of a bed for animals, showing my new design in a first configuration with the front doors closed;

FIG. 2 is a top, rear, right perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a top, front, right perspective view of the bed for animals, shown in a second configuration with the front doors opened outward;

FIG. 8 is a top, rear, right perspective view of the bed for animals, shown in a third configuration with the front-right door open; and,

FIG. 9 is a top, rear, left perspective view of the bed for animals, shown in a fourth configuration with the front-left door open.

In the drawings, the equal-length broken lines depict portions of the bed for animals that form no part of the claimed design.

1 Claim, 9 Drawing Sheets
